ATTORNEY

UNITED STATES PATENT OFFICE.

FRED W. SAWTELLE, OF OSHKOSH, WISCONSIN.

PACKAGE-TIE.

1,230,522.

Specification of Letters Patent. Patented June 19, 1917.

Application filed April 5, 1916. Serial No. 89,142.

To all whom it may concern:

Be it known that I, FRED W. SAWTELLE, a citizen of the United States, residing at Oshkosh, in the county of Winnebago and State 5 of Wisconsin, have invented certain new and useful Improvements in Package-Ties, of which the following is a specification.

This invention relates broadly to package ties, and has for its primary object, the 10 vision of an improved tying device, or connection, whereby the package or article may be readily tied and untied, such as condition or preference may dictate.

Another important characteristic of the 15 invention resides in the novel construction of the device, the same being so formed, as to enable the user to readily connect the various complemental parts of the device and to securely hold the same in their connected positions, by the mere bending of locking or fastening members.

It is further contemplated by the invention to provide a device of the character described, which is simple in construction, thus 25 allowing the same to be readily manufactured at a minimum cost; one which is strong and durable in use and finally, highly efficient for the purpose for which it is designed.

30 The improvements in the details and arrangement of parts will be apparent from an inspection of the accompanying drawings, in connection with the specific description hereinafter contained and wherein, the 35 preferred embodiment of the invention is disclosed for the purpose of imparting a full understanding of the invention.

In the drawings,

40 Figure 1 is a perspective showing the device applied;

Fig. 2 is a top plan of the several parts as stamped;

Fig. 3 is a longitudinal section, showing the several parts connected; and

45 Fig. 4 is a transverse section, also showing the parts connected.

Referring now more particularly to the drawings, wherein like reference numerals refer to like or corresponding parts throughout the several views, it may be stated, that the device comprises a receiving element 1, the said receiving element being constructed or stamped from a sheet of suitable metal or the like, and being substantially rectangular 50 in shape, the outer extremity of the same being curved or rounded as at 2. Arranged

in the said outer extremity and adjacent the curved portion 2, is an opening 3, which may be of any suitable configuration, but has been shown in this particular embodiment as 60 circular. Arranged in the adjacent or remaining extremity of the receiving element 1 is a second opening, 4, which also, may be of any configuration although the same has been, in this specific embodiment, illustrated 65 as squared. The connecting element 5, may be stamped from a single piece of metal or the like, thereby adding to the pecuniary value of the device as an article of manufacture. This connecting element is provided with a rounded outer extremity, as at 6, while the inner or remaining extremity has arranged thereupon laterally extending fingers 7 and 8, the said fingers 7 and 8 being severed from the adjacent extremity of 70 the element 5, as at 9, while the same have arranged thereon, adjacent their base portion, a distended finger 10. An opening 11 is arranged in the element 5 adjacent the curved or rounded extremity 6, the purpose 75 of which shall be subsequently described.

In applying the device to a package or similar article, a cord or the like, as at 12, is passed through the opening 3 in the receiving element, the end being returned and 80 knotted upon the main body portion thereof, as at 13. When in this position, the connecting element with its laterally extending fingers 7 and 8 bent into an upright position, are received by the flared opening 4 85 in the receiving element, whereupon, the said laterally extending fingers 7 and 8 are then bent downwardly into a position substantially parallel with the receiving element, as shown to advantage in Fig. 4, thus, 90 serving to prevent disconnection of the elements 1 and 5. The cord 12 is then carried transversely of the package and downwardly, then backwardly, across the bottom of the package, upwardly, and crossed 100 into engagement with that portion of the cord as adjacent the receiving element 1, whereupon, the same is passed thereover and is then carried longitudinally about the package, the free end being finally secured 105 within the opening 11 and knotted, as at 14. It will be obvious, that when this operation has been completed, the package has been securely tied, and, will be permanently held so, until a person desires to untie the package. In this event, instead of unknotting 110 the cord mentioned, it is only necessary that

the laterally extended fingers 7 and 8 be again bent upwardly, whereupon the same may be readily withdrawn from the opening 4 in the receiving element 1, thus, allowing for an inspection of the contents of the package. I desire to have it understood, that the particular arrangement of the cord as above outlined, is not necessary but that any efficient arrangement thereof may be 10 sorted to, this particular form merely being illustrated for the purpose of convenience.

From the foregoing, it will be apparent that I have provided a so called package tie, 15 which is particularly desirable for use in conjunction with mailable matter, wherein, it is often necessary that the contents of the mailed package be examined, in accordance with certain postal requirements. It 20 will also be appreciated, that the device due to its construction, may be readily classified as an article of manufacture.

While I have herein disclosed a specific embodiment of the invention, it will be apparent to persons skilled in the art, that the 25 invention is capable of embodiment in other forms and devices differing in detail and arrangement from that shown, as may be within keeping with the hereto appended 30 claims.

Having thus described my invention, what I claim is:—

1. A package tie, including a receiving element having an aperture therein, a connecting element, bendable fingers formed on the sides of said connecting element adapted for reception in the aperture in said receiving element, and a longitudinally extending finger formed upon the connecting element adjacent the bendable fingers engageable with the under face of the receiving element, as and for the purpose set forth.

2. An article of manufacture of the character described, consisting of a receiving element stamped from a single piece of material, means arranged upon said receiving

element for receiving one end of a flexible tying member, said receiving element having an opening arranged adjacent the remaining end thereof, a connecting element stamped from a single piece of material, means arranged upon said connecting element for receiving the remaining end of said flexible tying member, bendable fingers extending from and arranged adjacent one extremity of said connecting element, a longitudinally extending finger formed upon the connecting element adjacent said bendable fingers, the bendable fingers being received by the last mentioned opening in said receiving element and adapted to be bent thereover for providing a connection between said receiving and connecting elements.

3. An article of manufacture of the character described, consisting of a receiving element stamped from a single piece of material having an aperture arranged in the outer extremity thereof for receiving one end of a flexible tying member, an aperture arranged in the inner extremity of said receiving element, a connecting element stamped from a single piece of material and having an aperture arranged in the outer extremity thereof for receiving the remaining end of said flexible tying member, bendable fingers formed upon the inner extremity of said connecting element, a longitudinally extending finger formed upon the connecting element adjacent said bendable fingers, the bendable fingers being adapted to be engaged with the last mentioned aperture in said receiving element whereby a connection between the receiving and connecting elements will be afforded.

In testimony whereof I affix my signature in presence of two witnesses.

FRED W. SAWTELLE.
